(57) **CLAIM**

The ornamental design for a hood for a polishing, grinding, buffing and finishing machine, as shown and described.

DESCRIPTION

FIG. 1 is a perspective view of my hood for a polishing, grinding, buffing and finishing machine;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a back elevational view thereof;

FIG. 8 is a perspective view of another embodiment of my hood for a polishing, grinding, buffing and finishing machine;

FIG. 9 is a top plan view thereof;

FIG. 10 is a bottom plan view thereof;

FIG. 11 is a left side elevational view thereof;

FIG. 12 is a right side elevational view thereof;

FIG. 13 is a front elevational view thereof; and,

FIG. 14 is a back elevational view thereof.
